Attorney

Inventor

UNITED STATES PATENT OFFICE

ROBERT VAN SICKLER, OF WASHINGTON, DISTRICT OF COLUMBIA, ASSIGNOR TO
AMERICAN LEAD PENCIL COMPANY, A CORPORATION OF NEW JERSEY

AUTOMATIC TELEPHONE-DIAL-OPERATING PENCIL ATTACHMENT

Application filed August 12, 1930. Serial No. 474,794.

This invention relates generally to improvements in pencils, and the like, but has particular reference to improvements in attachments for pencils and similar instruments by means of which such instruments can conveniently be used for such purposes as operating the call dials of automatic telephones and also to allow for the use of the eraser end of a pencil without removing the attachment therefrom.

In automatic telephone practice, as is well known, to make an erasure it is necessary either to remove the dialing attachment from the pencil or to use another pencil or an eraser. The purpose of my invention is intended to eliminate this inconvenience by providing a pencil dialing attachment that makes allowance for the use of the eraser end as well as the pencil end.

20 A further object of my invention is to provide means for adjustment to compensate for the wear on the eraser.

Another object of my invention is to provide a device of the character indicated which 25 can be manufactured at a low cost, but which will nevertheless be durable and otherwise satisfactory.

With these and other objects in view, the invention consists in the construction, combination and arrangement of parts as will be hereinafter more fully described, illustrated in the accompanying drawings and pointed out in the claims hereunto appended.

In the drawings:

35 Figure 1 is an elevation of a pencil equipped with one of the improved devices;

Fig. 2 is a view similar to Fig. 1 but shows a cross-section of the attachment in its relation to a pencil;

40 Fig. 3 shows a fragmentary view of the device in its application to an automatic telephone dial;

Fig. 4 is a perspective of the attachment;

Fig. 5 is a cross-section of a modification 45 of my invention; and

Fig. 6 is an elevation of another modification of my invention.

The construction shown in the drawings is adapted to use with an ordinary lead pencil 50 and eraser 10. It comprises an apertured

member or a spring metal sleeve or cap 11 having a vertical slot 12 provided in the circular wall thereof. The member or cap 11 is adapted to fit over the top of some such object as a pencil or the like. The member or cap 11 may be provided on its inner periphery with corrugations 13 and studs 14 to engage the sides of the pencil 10 to hold the device in engagement with the pencil shaft and also to allow for adjustment of the attachment on the pencil. The member or cap 11 preferably has a spherical or bulbous portion 15 which may be integral therewith and having an aperture 16 which is in alignment with an aperture 17 in the base of the sleeve 11 to allow for the reception of the pencil 10.

In the construction shown in Fig. 3 the device is shown in operating position, the portion 15 being of a slightly larger diameter than the opening 18 in dial plate 19 of the automatic telephone 20. By this arrangement the eraser end of the pencil 10 will not touch upon the number plate 21 to cause the numerals and letters on the plate to be obliterated or retard the dialing action by contact with the number plate.

In the modification shown in Fig. 5 I have provided a portion 15' having an inwardly extending sleeve member 11' and aligned openings 16' and 17' for the reception of the pencil and means for retaining said pencil as indicated by studs or prongs 14'.

In the modification shown in Fig. 6, I have provided a portion 15" having a sleeve 11" integral therewith, said sleeve having 25 a plurality of flat surfaces 22 to prevent pencil attachment from rolling off a flat surface.

While the constructions shown and above described are entirely satisfactory for the purposes primarily set forth, the ideas are 90 capable of various embodiments, with suitable modifications and changes, all coming within the scope of the claims which follow.

I claim:

1. An attachment for pencils and the like, comprising an adjustable sleeve member having a spherical portion and aligned openings therein for the reception of the body and eraser of a pencil, said spherical portion having a diameter in excess of the diameter of 100

- the openings of an automatic telephone dial.
2. An attachment for pencils for operating the dial of an automatic telephone and the like comprising an adjustable sleeve member having a spherical portion and aligned openings therein for the insertion of a pencil, permitting the eraser to extend beyond said spherical portion for ready use, the spherical portion having a diameter slightly in excess of the diameter of the telephone dial openings, to provide an operating connection therewith, while maintaining clearance between the eraser end of the pencil and the dial.
- 15 3. A telephone dial operating pencil attachment comprising pencil engaging sleeve, an integral ball shaped portion having an opening therein to permit use of an eraser on the end of said pencil and means for adjusting said sleeve to compensate for wear on said eraser.
- 25 4. An attachment for pencils and the like comprising an internally corrugated telephone dial operating member having a spherical portion provided with an opening adapted to expose the eraser of a pencil and prongs on the tubular portion adapted to engage said pencil and hold said member in position for operating a telephone dial.
- 30 5. An attachment for pencils and the like, comprising an adjustable sleeve member having a spherical portion and aligned openings therein for the reception of the body and eraser of a pencil, said spherical portion having a diameter in excess of the openings of an automatic telephone dial, said spherical member having flattened portions extending around its circumference on a line at right angles to the sleeve member.
- 40 6. An attachment for pencils and the like for operating the dial of an automatic telephone comprising substantially a spherical member apertured to provide opposed terminal openings adapting it to be mounted on a pencil adjacent the butt end of the same, and adapting it to expose an eraser at the side opposite that from which the pencil extends and beyond the dial operating surface of the attachment.
- 45 7. An attachment for pencils and the like for operating the dial of an automatic telephone comprising an apertured member having a spherical enlargement of a maximum diameter slightly in excess of the diameter of the openings of a telephone dial, said member having provision for slidably mounting the same upon the pencil for adjustably positioning it adjacent the eraser end of the same in dial operating position and to regulate the degree to which the eraser end may extend beyond the member for ready use.

In testimony whereof, I have signed my name to this specification.

ROBERT VAN SICKLER.
